UNITED STATES PATENT OFFICE.

JOHN P. INMAN AND ROBERT E. ESTES, OF MIDLAND, TEXAS.

SPARK-PLUG.

1,136,961.

Specification of Letters Patent.

Patented Apr. 27, 1915.

Application filed November 11, 1913. Serial No. 800,282.

To all whom it may concern:

Be it known that we, JOHN P. INMAN and ROBERT E. ESTES, citizens of the United States, residing at Midland, in the county of 5 Midland and State of Texas, have invented certain new and useful Improvements in Spark-Plugs, of which the following is a specification.

Our invention relates to improvements in 10 spark plugs, such as are used in explosive engines, and one object of the invention is to provide means whereby the electrodes of the spark plug may be readily cleaned while the motor is running, and whereby the electrodes may be adjusted into greater or less 15 contiguity with each other, so as to thereby adjust the distance across which the spark will jump.

A further object of the invention is to so 20 construct the base of the spark plug that by removing the porcelain insulator and the bushing supporting it, a tire pump may be connected with the plug base, thus doing away with the necessity of removing the 25 plug entirely from the cylinder of the engine and inserting the pipe of the tire pump in engagement with the screw threads of the cylinder. The reason for this is that the engagement and disengagement of the tire 30 pump pipe with the screw threads of the cylinder tends to wear the screw threads in cylinder. The spark plug base, however, may be readily removed and replaced at any time if the threads are worn in plug base.

35 A further object of the invention is to provide a spark plug so constructed as to permit gasoline or other liquid to be poured through the plug whereby to prime the motor or to clean the plug.

40 A still further object is to provide a plug of the character stated, very simply and cheaply constructed wherein all the parts are readily removable and replaceable.

Our invention is illustrated in the accompanying drawings, wherein:—

Figure 1 is a longitudinal section of a 50 spark plug constructed in accordance with our invention. Fig. 2 is a perspective view of the electrode pin. Fig. 3 is a perspective view of the cap supporting the electrode pin and of the lock nut thereon.

Corresponding and like parts are referred to in the following description and indicated in all the views of the accompanying drawings by the same reference characters.

Referring to these drawings, 2 designates

the plug base. The lower portion 3 of this base is cylindrical in form and exteriorly screw-threaded, as at 4. The upper portion 5 of the base is also cylindrical in form but 60 has an internal diameter equal to the external diameter of the portion 3. The upper portion of the base is internally screw-threaded as at 6. Engaging the upper portion of the base is a clamp bushing 7 which 65 is exteriorly screw threaded and formed with a head whereby it may be rotated. Fitting within the base 2 is the porcelain insulator 8 which is formed intermediate its ends with an annular flange or shoulder 9. The 70 diameter of the flange or shoulder is equal to the interior diameter of the base. The insulator below the shoulder 9 has an interior diameter equal to the interior diameter of the portion 3 of the base while the upper 75 portion of the insulator above the shoulder 9 is sufficiently smaller in diameter than the upper portion of the base 5 to permit the insertion of the bushing 7.

Mounted upon the upper end of the insulator is the cap or head 10. This cap is cylindrical in form and is provided intermediate its ends with the annular flange 11 which fits upon the upper end of the insulator. The lower end of the cap fits into 80 the annular recess formed in the upper end of the insulator. The cap is interiorly screw-threaded as at 12, these screw-threads extending the full length of the cap. Disposed within the insulator is the metallic 85 sleeve 13, the upper end of which is screw threaded for engagement with the lower end of the cap 10 and the lower end of the sleeve is enlarged as at 14, the lower end of the hollow interior of the insulator being enlarged as at 15 to accommodate this enlargement of the cap. A gasket 16 of copper or 90 asbestos is disposed between the flange 9 of the insulator and the shoulder 17 of the base.

Passing through the center of the sleeve 13 is the electrode pin 18 which is enlarged at its upper end as at 19, this enlargement being screw-threaded to engage the screw threads 12 on the cap 10. The electrode pin 18 fits the sleeve 13 snugly and projects below the lower end of the sleeve and its lower extremity is disposed in contiguity with the electrode bar 20. This electrode bar and the electrode pin are preferably made of 1 nickel. The upper end of the electrode pin is formed with a head 21 having means

whereby the electrode pin may be rotated, this means preferably being a notch or nick 22 extending transversely across the upper face of the head. A lock-nut 23 engages 5 the screw threaded portion 19 and bears against the upper end of the cap 10. This lock-nut is preferably formed with laterally extending wings or prolongations 24 so that it may be readily manipulated without 10 the necessity of using a wrench. These wings permit the nut to be turned by means of a stick or any like member of insulating material. The wires energizing the electrode 18 are secured to the cap 10 by means 15 of a clamp nut 25 which engages the screw threads 26 formed upon the exterior of the upper end of the cap 10. When the clamp nut 25 is turned down it binds the conducting wires between the clamp nut and the 20 flange 11.

The particular object of forming the upper portion 5 of the base 2 with an interior diameter equal to the exterior diameter of the lower portion 3 is to permit the pipe 25 leading to a tire pump to be inserted in the plug base instead of having to remove the plug entirely from the cylinder. This obviates the wear on the threads of the cylinder and it will be obvious, also removes the 30 necessity of entirely removing the spark plug in order to connect said tire pump with the cylinder.

While we do not wish to limit ourselves to the number of threads on the portion 19 35 of the electrode pin, preferably this pin has thirty-two threads to the inch, so that one full turn of the electrode pin in one direction will give a gap between the lower end of the pin and the bar 20 one thirty-second 40 of an inch wide. To set spark gap at one sixty-fourth of an inch, the electrode pin 18 is turned half around. It will be understood that this ratio between the amount of rotative movement of the pin and the gap 45 between the lower end of the pin and the bar 20 may be changed to any extent desired. By adjusting the pin 18 in the cap 10 the gap between the bar 20 and the lower end of the pin may be accurately adjusted to 50 any extent desired, and it is obvious also that the amount of this adjustment may be accurately determined by the number of rotations given to the head 21. Furthermore it will be obvious that by rotating the pin 55 so as to shift it downward and bring its lower end into engagement with the projection 20^a on the electrode bar 20 the plug can be cleaned while the motor is running. After the spark points are cleaned it is an 60 easy matter to return the electrode to its original position.

It will be seen that the electrode pin 18 may be entirely removed from the plug and that when so removed, gasoline or other liquid may be poured through the plug into

the cylinder, thereby to clean or prime the motor or to clean the plug.

Gaskets 27 and 28 are disposed, the first under the nut at the upper end of the sleeve 13 and the other between the enlarged lower 70 end of the sleeve and the shoulder on the insulator. These gaskets make a gas-tight joint at all times and compensate for the expansion and contraction of the sleeve. The gaskets are made of material having a 75 greater coefficient of expansion and contraction than the sleeve, and it will therefore be obvious that the expansion and contraction of the sleeve and the gaskets are opposed.

While we do not wish to limit ourselves to the material from which the plug is made, we find in practice that it is best to make the base, bushing and cap, of iron or steel; the insulator of porcelain, and the 85 electrode pin or bar of nickel.

It is likewise to be noted that the insulating core 8 is easily removable from the base by simply removing the bushing 7, thus permitting the ready introduction of a new 90 insulator at any time.

It is to be noted that not only is the upper portion of the plug base of the same diameter as the internal diameter of the lower portion of the plug base, but the screw 95 threads have the same pitch.

Having thus described the invention what is claimed as new is:—

1. In a spark plug, an insulator having a bore extending longitudinally therethrough, 100 a sleeve fitting the bore, the upper end of the sleeve extending beyond the upper end of the insulator, an electrode passing through the sleeve, and a cap resting upon the upper end of the insulator and engaging with the upper end of the sleeve, having independent screw threaded engagement with the upper end of the electrode.

2. In a spark plug, an insulator having a bore extending longitudinally therethrough, 110 a sleeve screw-threaded at its upper end and enlarged at its lower end passing through said bore, a cap disposed upon the upper end of the insulator and interiorly screw threaded to engage said sleeve, an electrode pin 115 passing through the sleeve and insulator and having screw threaded engagement at its upper end with said cap.

3. In a spark plug, an insulator having a bore extending longitudinally therethrough, 120 a sleeve screw-threaded at its upper end and enlarged at its lower end passing through said bore, a cap disposed upon the upper end of the insulator and interiorly screw-threaded to engage said sleeve, an electrode 125 pin passing through the sleeve and insulator and having screw-threaded engagement at its upper end with said cap, whereby the electrode pin may be longitudinally adjusted with relation to the cap and sleeve, and 130

means for locking the electrode pin in any adjusted position.

4. In a spark plug, an insulator having a longitudinally extending bore, a sleeve fitting said bore and having an enlarged lower end, the upper end of the sleeve being exteriorly screw-threaded, a cap on the upper end of the insulator having screw-threaded engagement with the sleeve and extending 10 beyond the sleeve, an electrode pin passing through the sleeve and said cap, and having screw-threaded engagement with the cap, and means for locking the electrode pin in any desired position.
5. In a spark plug, a tubular insulator, a tubular sleeve disposed therein, a tubular cap on the insulator, and an electrode pin passing through the sleeve and insulator and having screw-threaded engagement at its 20 upper end with said cap said sleeve having screw threaded engagement with the cap.

6. In a spark plug, a tubular insulator, a tubular member passing through the insulator and engaged therewith against upward 25 movement, an electrode pin screw-threaded at its upper end, and a member mounted upon the insulator through which the electrode pin passes and with which the screw threads of the electrode pin have engagement, said member having screw threaded 30 engagement with the first-named member whereby to permit the electrode pin to be entirely removed from the insulator to thereby permit the introduction of liquids into the cylinder through the insulator.

7. In a spark plug, a tubular insulator having a central bore, the upper end of the insulator being recessed immediately surrounding the bore, a cap mounted on the upper 40 end of the insulator and having interior screw threads, said cap extending down into the said recess, a sleeve disposed within the insulator bore having an enlarged lower end, the upper end of the sleeve having screw-threaded engagement with the lower 45 end of the cap, and an electrode pin having a smooth surface passing through the sleeve, the upper end of the electrode pin having screw-threaded engagement with said cap.

8. In a spark plug, a tubular insulator having a central bore, the upper end of the insulator being recessed immediately surrounding the bore, a cap mounted on the upper end of the insulator, said cap extending 55 down into the said recess, a sleeve disposed within the insulator bore having an enlarged lower end, the upper end of the sleeve having screw-threaded engagement with the lower end of the cap, an electrode pin having a smooth surface passing through the sleeve, the upper end of the electrode pin 60

having screw-threaded engagement with said cap, and a lock-nut engaging the screw threaded portion of the pin and bearing against the upper end of the sleeve.

9. In a spark plug, a plug base enlarged at its upper end, the exterior of the lower end being threaded to engage a compression chamber, the interior of the upper end being threaded, a tubular insulator, the lower end 70 of which fits the lower end of the plug base, a clamp bushing engaging the insulator and the upper end of the plug base, a sleeve disposed within the insulator, a tubular cap upon the insulator interiorly screw threaded 75 for its entire length, the upper portion of said cap being exteriorly screw threaded, an electrode pin having a smooth surface for the greater portion of its length and passing through the sleeve, the upper portion of the 80 pin being enlarged and screw-threaded to engage the screw threads of the upper portion of the cap, a head on said electrode pin whereby it may be rotated, a lock-nut engaging the screw threads of the electrode 85 and bearing against the upper end of the cap, and a wire clamp nut engaging said cap.

10. In a spark plug, an insulator having a central bore enlarged at its upper end, a tubular element disposed in the enlarged upper portion of the bore of the insulator, the interior diameter of said tubular element being the same as the interior diameter of the contracted portion of said central bore, 90 said tubular element being interiorly screw-threaded, and an electrode passing through the bore of the insulator and having screw threads at its upper end engaging with said tubular member, whereby to permit the removal of the electrode and permit the introduction of liquid into the cylinder through the plug.

11. In a spark plug, an insulator having a longitudinally extending bore, a sleeve fitting said bore and having an enlarged lower end, a cap on the upper end of the insulator having screw-threaded engagement with the sleeve, an electrode pin passing through the sleeve and the cap, and gaskets disposed between the cap and the insulator and between the enlarged end of the sleeve and the insulator, said gaskets having a greater coefficient of expansion and contraction than the sleeve and cap.

In testimony whereof we affix our signatures in presence of two witnesses.
